CLAIM

The ornamental design for the hydro-massage appliance, as shown and described.

DESCRIPTION

FIG. 1 is a perspective view of a hydro-massage appliance showing the new design;

FIG. 2 is a front elevational view of the blower unit thereof;

FIG. 3 is a rear elevational view of the blower unit thereof;

FIG. 4 is a left side elevational view of the blower unit thereof;

FIG. 5 is a right side elevational view of the blower unit thereof;

FIG. 6 is a top plan view of the mat thereof;

FIG. 7 is a left side elevational view of the mat thereof;

FIG. 8 is a right side elevational view of the mat thereof; and

FIG. 9 is an end elevational view of the mat hereof;

FIG. 10 is an end elevational of the mat thereof opposite from FIG. 9; and

FIG. 11 is a bottom plan view of the mat thereof.
